THOMAS W. THOMAS.
INVENTOR

BY *James J. Givens*
ATTORNEY

UNITED STATES PATENT OFFICE

2,504,092

WATER HEATER

Thomas W. Thomas, Portland, Oreg.

Application November 30, 1945, Serial No. 631,855

1 Claim. (Cl. 122—17)

1

This invention relates to improvements in water heaters and has for one of its principal objects the provision of means for heating water more quickly and economically than water heaters now common in the art.

A further object is the provision of means to automatically break any vacuum in the water supply line should the water be shut off to prevent a "back flow" caused by syphonic action. This same "back flow" preventative means also prevents excessive water supply being forced into the heater, thus causing less mixture of cold water with the hot water at the top of the heater.

A further object of the invention is the provision of means for automatically flushing the heater to remove lime, scale, rust or other like residue which would otherwise be drawn up through the heater and mixed with the water content thereof.

A still further object of the invention is the provision of baffles in spiral form surrounding the water tank for circulating heat spirally around the tank to enable the contents of the tank to partake of its temperature. Moreover, the heat emanating from the spirals may be further utilized by directing it to a point of use through any approved form of ducts or the like.

The foregoing and other objects will be apparent as my invention is more fully hereinafter described in the following specification, illustrated in the accompanying drawing, and finally pointed out in the appended claim.

In the drawings:

Figure 1 is a vertical sectional elevation of a water heater made in accordance with my invention.

Figure 2 is a slightly reduced fragmentary elevation of Figure 1 with a fragment broken away for convenience of illustration.

Figure 3 is an enlarged sectional plan view taken on the line 3—3 of Figure 1.

Figure 4 is a perspective detail view of means used for forming a residue flushing chamber at the lower end of the water tank of the heater.

Figure 5 is a slightly enlarged obverse perspective view of Figure 4.

Referring now more particularly to the drawings:

Reference numeral 1 indicates generally a housing which consists of an outer cylindrical shell 2, an inner shell 3 and suitable insulating material 4 disposed therebetween. The upper end of the housing is closed by a lid 5 of spaced-apart double wall construction as shown and secured by a flange 6 to the outer periphery of the

2

housing 1 by welding or the like. The air space between the double walls of the lid serves as an insulator. Extending through and secured to the lid 5 by means of a flange 7 is a tube 8 which terminates at its lowermost end in a disc 9.

Disposed within the housing 1 and in spaced relation to the interior walls 3 thereof is a tank 10 closed at its top and bottom ends as at 11 and 12 respectively. Extending through said top and bottom closures is a conduit 13 open at both of its ends as shown. The uppermost end of the conduit is in open communication with the space between the tank and the housing. The lowermost end of the conduit is in open communication through a disc 14 with a combustion chamber generally indicated at 15 within which is disposed a heating element of any approved form indicated at 16 and adapted to apply heat directly to the disc 14.

20 The disc prevents excessive heat from contacting the bottom of the tank and serves to retain the heat and cause greater circulation between the hot air rising and the cold air returning to the combustion chamber.

25 Disposed above the bottom end of the conduit 13 is a disc 17 from which depends an annular collar 18 formed with circumferentially spaced apart openings 19 formed by punching out portions 20 of the collar and bending the portions 30 outwardly into a flushing chamber 20A defined by the disc 17 and the bottom 12 of the tank. At radially disposed points about the center of the disc 17 there form apertures 21 whose downwardly inclined tongue portions 22 are directed toward 35 the various openings 19 in the depending collar 18 for directing water from the tank around the flushing chamber and out through the openings 19 to be finally discharged through a drain valve 19A.

40 Surrounding the tank 10 is a spiral baffle 23 of light weight material having spaced apart depending baffle plates 24. The baffle and baffle plates may be stamped out of one piece of sheet metal.

45 The coils of the spiral 23 are spaced apart sufficiently to allow heat to rise and as the heat reduces in temperature it circulates back toward the combustion chamber. The baffle plates 24 hold the circulating heat in pockets, and they are 50 so spaced as to allow complete circulation of hot and cold air. The baffle in conjunction with baffle plates may be used in the internal flue or flues by reversing its structure.

Extending through the lid 5 and into the top 55 of the tank 10 is a water outlet indicated at 25

and in communication with conventional water distributing pipes. Also extending through the top of the tank is a water inlet 26 restricted or reduced in diameter as at 27 near its lower end. Directly beneath this reduced end of the inlet 26 is a diagonal slot 28 to serve as a vacuum breaker in the water supply line should the water be shut off, and thus prevent any backflow caused by syphonic action. The slot prevents excessive water supply being forced into the heater, and thus causes less mixture of cold water with the heated water at the top of the tank. The lowermost end of the inlet 26 is connected by a coupling 29 with one end of a water coil whose opposite end terminates just above the disc 17 as shown and adapted to direct incoming water through the openings 21 into the flushing chamber 20A. The water in the tank is then heated by the burner 16. At predetermined intervals the drain valve 19A is opened to drain off any lime, scale, rust or other residue which may have accumulated within the flushing chamber.

The incoming water within the coil 30 partakes of the temperature of the water in the tank. The bottom open end of the coil directs the incoming water directly onto the heated plate 17 and is thereby preheated.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

A water heater consisting of an insulated housing, a tank disposed within the housing in

spaced relation thereto, baffles disposed between the tank and the housing, a conduit open at both of its ends extending through the tank and flanged at its lower end, a heating element disposed beneath the flanged end of the conduit, a disc having a depending annular wall disposed above the flanged end of the conduit to form a flushing chamber, openings formed in said disc and its said depending wall, a water inlet and a water outlet extending into the upper end of the tank, said inlet connecting with one end of a water coil disposed within the tank and whose opposite end terminates on the top surface of said disc for directing a portion of the incoming water through said openings in the disc and its depending wall into said flushing chamber, said inlet being reduced in diameter adjacent its point of connection with the said one end of the water coil, a vacuum breaker in the form of a diagonal slot formed in said inlet between said reduction in diameter of the inlet and its said point of connection with the water coil, and an outlet for draining the contents of the flushing chamber.
